(57) **CLAIM**

The ornamental design for a notebook, as shown and described.

DESCRIPTION

FIG. 1 is a top perspective view of a notebook, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged view of the encircled portion '9' in FIG. 1;

FIG. 10 is an enlarged view of the encircled portion '10' in FIG. 2;

FIG. 11 is an enlarged view of the encircled portion '11' in FIG. 3;

FIG. 12 is an enlarged view of the encircled portion '12' in FIG. 4;

FIG. 13 is an enlarged view of the encircled portion '13' in FIG. 5;

FIG. 14 is an enlarged view of the encircled portion '14' in FIG. 6;

FIG. 15 is an enlarged view of the encircled portion '15' in FIG. 7;

FIG. 16 is an enlarged view of the encircled portion '16' in FIG. 8;

FIG. 17 is an enlarged view of the encircled portion '17' in FIG. 8;

(Continued)

FIG. 18 is an enlarged view of the encircled portion '18' in FIG. 7; and,
FIG. 19 is an enlarged view of the encircled portion '19' in FIG. 7.

The broken lines illustrating portions of the notebook form no part of the claimed design. The dot-dash broken lines encircling enlargement portions of the claimed design form no part of the claimed design.

1 Claim, 16 Drawing Sheets

(58) Field of Classification Search

CPC G06F 1/1616; G06F 1/1633; G06F 1/1656

See application file for complete search history.
